ELECTRIC SWITCH

Robert F. Sambleson, Bridgeport, Conn., assignor
to General Electric Company, a corporation of
New York

Application November 15, 1935, Serial No. 49,929

11 Claims. (Cl. 200—153)

The present invention relates to electric switches of the type having liquid contact circuit closers for controlling the flow of current.

The object of my invention is to provide an improved construction and arrangement in switches of this type, and for a consideration of what I believe to be novel and my invention attention is directed to the accompanying description and the claims appended thereto.

In the accompanying drawing, Fig. 1 is a sectional side elevation taken on line 1—1 of Fig. 2 of a switch embodying my invention; Fig. 2 is a top plan view partly broken away of the switch shown in Fig. 1; Fig. 3 is a sectional elevation taken on line 3—3 of Fig. 1; and Fig. 4 is a diagrammatic view showing the construction and operation of the liquid contact circuit closers.

Referring to the drawing, I have illustrated my invention using four liquid contact circuit closers, each having a pair of cup-shaped metal terminals 1 which are separated by an insulating diaphragm 2 of a refractory material, such as a ceramic material. The edges of the terminals are sealed by a bead 3 of glass which also seals the junctions between the diaphragm and the terminals. Within the space enclosed by the terminals is a suitable quantity of mercury 4 which forms the conducting medium between the terminals. In the manufacture of the circuit closer, the space enclosed by the terminals is evacuated and filled with hydrogen at a pressure of one or more atmospheres which increases the current interrupting capacity of the circuit closer. The diaphragm 2 is provided with an opening 5 which is submerged in the mercury when the circuit closer is in the current conducting position. When the circuit closer is in the current-interrupting position the opening 5 is above the mercury, and the circuit between the terminals is therefore broken by the insulating diaphragm 2. Due to the construction of the circuit closer, the interruption of the circuit between the terminals takes place in the mercury as the circuit closer is turned so that the opening 5 in the diaphragm is lifted from the mercury. The above described construction is illustrative of liquid contact circuit closers which are suitable for use in a switch embodying my invention.

The circuit closers are arranged in a housing 6 of molded insulating material in pairs with the inner terminals of each pair of circuit closers opposite each other and the outer terminals of each pair adjacent the side walls of the housing. Between the inner terminals of each of the pairs

of circuit closers is a U-shaped contact 7 having a projection 8 on each arm which fits into a depression 9 in the terminal of the adjacent circuit closer. Each of the contacts 7 is pivotally connected by means of a rivet 10 to a contact strip 11. If desired, this connection may be rigid in order to improve the conductivity. The contact strip 11 lies along the bottom wall of the housing and, as shown in Fig. 3, a clearance hole 12 for the rivet 10 is provided in the bottom wall of the housing. The contact strip 11 is secured to the housing by means of a spun-over portion 13 of an insert 14 molded in the housing. A terminal screw 15 is threaded into the insert and provides a terminal for attaching the line conductor. The pivotal connection between the contacts 7 and the terminal strips 11 permits the contacts 7 to extend in opposite directions from the ends of the contact strips 11, and thereby permits the use of identical parts 11 while still permitting the contact strips 11 to terminate in terminals at the same end of the housing. Between the side walls of the housing and the outer terminals of the circuit closers are contact strips 16 each provided with two projections 17 which fit respectively into a depression 18 in each of the outer terminals of the circuit closers. The projections 8 and 17 provide ball and socket connections between the contacts and the terminals of the circuit closers 30 and thereby support the circuit closers for rotation about their axes and also conduct current to the terminals. The wiping action between the contacts and the terminals prevents increase of contact resistance. The side walls 35 of the housing prevent spreading of the contacts 16 and thereby hold the circuit closers in assembled relation. The contact strips 16 are secured to the housing in the same manner as the contact strips 11.

The terminals 1 are provided with depressions 19 and between the adjacent terminals of each pair of circuit closers extends a pin 20, the ends of which fit into the depressions 19. The pins 20 are carried by a link 21 which comprises two 45 spaced strips 21a of insulating material which are arranged between the arms of the U-shaped contacts 7. The link 21 and the pins 20 connect the circuit closers so that they rotate in unison. The upper surface of the strips 21a is flat, and springs 22 which bear on this surface hold the pins 20 in the depressions 19. The springs 22 also exert a downward force on the circuit closers through the pins 20 and press the depressions 9 and 18 in the terminals against 50 55

the projections 8 and 17 of the contacts, thereby increasing the contact pressure. The spring strips 22 are held in place by a mounting strap 23 which is secured across the upper end of the housing by screws 24. A tongue 22a on each of the strips 22 bears against the end wall of the housing and prevents turning of the strips. The mounting strap is provided with depending ears 25 between which is pivoted a pin 26 to which a handle 27 is secured. The handle is provided with a rigid projecting link 28 having an open slot 29 in its end which fits over a pin 30 carried between the insulating strips 21a. As the handle is pivoted between the ears 25 the 10 sliding connection provided between slot 29 and the pin 30 causes the link 21 to be reciprocated and thereby causes the circuit closers to be rotated. During the reciprocation of the link 21, the pins 20 pivot in the depressions 19 and the 15 springs 22 hold the pins 20 in the depressions 19. During the reciprocation of the link 21, the link has a movement toward the bottom of the housing as the link is on either side of the central position, and the springs 22 therefore tend 20 to hold the link in either of its extreme positions.

In the assembly of the switch, the liquid contact circuit closers are assembled between the contacts 7 and 16, the contacts being arranged 25 as shown in Fig. 2. The assembly is then inserted in the housing and the contacts secured to the housing by the spun-over portions 13 of the inserts 14. When in this position, the side walls of the housing prevent spreading of the 30 contacts 16, and the circuit closers are therefore securely held within the housing and supported for rotation about their axes. The link 21 is then placed between the circuit closers and the circuit closers are turned so that the pins 20 fit in the 35 depressions 19. Spring strips 22 are then placed on the top of the housing, and the mounting strip 23 is secured to the housing clamping the spring strips 22 in place. During this latter assembly, the slot 29 is placed over the pin 30 on 40 the link 21.

In the use of the switch, the switch is mounted in an outlet box, the right-hand end of the mounting strap 23 being at the upper end of the outlet box. When in this position, the circuit connections and the operation of the switch 45 is diagrammatically illustrated in Fig. 4. For convenience, the terminals of the switch have been labeled A, B, C, and D, and the position of the handle 27 has been diagrammatically shown on each of the circuit closers. As is apparent from Fig. 4, when the handle 27 is in the raised position, a circuit is completed from terminal B to terminal C and from terminal A to terminal D. When the handle 27 is in the 50 lower or dotted line position a circuit is completed between terminal B and terminal D and between terminal A and terminal C, and the circuits mentioned in the preceding sentence are broken. The switch therefore provides a double-pole reversing switch or a four-way switch in 55 which the making and breaking of each circuit is effected by means of a separate liquid contact circuit closer. It is apparent that by making suitable changes in the location of the openings 60 5 in the diaphragm 2 or the location of the depressions 19 that the switch can be arranged for mounting in other than a vertical position.

What I claim as new and desire to secure by Letters Patent of the United States, is:

75 1. In an electric switch, liquid contact circuit

closers each having an enclosure including opposed cup-shaped terminals, contacts engaging said terminals, said contacts and said terminals having complementary projections and depressions whereby the circuit closers are supported for rotation about the axes of their terminals, a reciprocable link pivotally connected to the circuit closers for operating the circuit closers, and resilient means engaging said link for exerting a force on the circuit closers transversely to their axes of rotation whereby the contact pressure between the terminals and the contacts is increased. 10

2. In an electric switch, liquid contact circuit closers each having an enclosure including opposed cup-shaped terminals, contacts engaging said terminals, said contacts and said terminals having complementary projections and depressions whereby the circuit closers are supported for rotation about the axes of their terminals, a reciprocable link connecting said circuit closers, the connection between said link and said circuit closers including depressions in said terminals and projections on said link fitting therein, and resilient means engaging said link for exerting a force on the circuit closers transversely to their axes of rotation whereby the contact pressure between the terminals and the contacts is increased. 15

3. In an electric switch, four liquid contact circuit closers each having an enclosure including opposed cup-shaped terminals, said circuit closers being arranged in pairs with the inner terminals of each pair opposite each other, a pair of contacts each frictionally engaging the inner terminals of one of the pairs of circuit closers, a pair of contacts each frictionally engaging two of the outer terminals of the circuit closers, said contacts and said terminals having complementary projections and depressions whereby the circuit closers are supported for rotation about the axes of their terminals, and means for rotating said circuit closers in unison, said circuit closers being arranged so that a circuit is completed from one of the contacts connected to the inner terminals of the circuit closers alternatively to one of the contacts connected to the outer terminals of the circuit closers. 20

4. In an electric switch, four liquid contact circuit closers, each having opposed terminals, said circuit closers being arranged in pairs with the inner terminals of each pair opposite each other, a pair of contacts each connected respectively to the inner terminals of one of the pairs of circuit closers, a pair of contacts each connected respectively to two of the outer terminals of the circuit closers on the same side of the switch, and means for rotating said circuit closers in unison, said circuit closers being arranged so that a circuit is completed from one of the contacts connected to the inner terminals of the circuit closers alternatively to one of the line contacts connected to the outer terminals of the circuit closers. 25

5. In an electric switch, four liquid contact circuit closers each having opposed terminals, said circuit closers being arranged in pairs with the inner terminals of each pair opposite each other, a pair of U-shaped contacts each frictionally engaging the inner terminals of one of the pairs of circuit closers, a pair of contacts each frictionally engaging two of the outer terminals of the circuit closers on the same side of the switch, and means for rotating said circuit closers. 30

cuit closers in unison, said circuit closers being arranged so that a circuit is completed from one of the contacts connected to the inner terminals of the circuit closers alternatively to one of the contacts connected to the outer terminals of the circuit closers.

6. In an electric switch, liquid contact circuit closers, means for supporting the circuit closers for rotation about spaced axes, a reciprocable link having pivotal connections with circuit closers whereby the circuit closers are rotated in unison, and resilient means engaging said link and exerting a force thereon perpendicular to the reciprocal movement thereof whereby the link is resiliently held at either end of its movement.

7. In an electric switch, electric contact circuit closers, means for supporting the circuit closers for rotation about said spaced axes, a reciprocable link, pivotal connections between said link and the circuit closers whereby the circuit closers are rotated in unison, at least one of said connections comprising a pin fitting in a depression, and means exerting a force on said link perpendicular to the reciprocal movement whereby said connection is maintained during the reciprocal movement of the link.

8. In an electric switch, liquid contact circuit closers, means for supporting the circuit closers for rotation about its spaced axes, a reciprocable link having projections therein fitting in complementary depressions in said circuit closers whereby the circuit closers are rotated in unison, and spring means exerting a force on said link holding said projections in said depressions during the reciprocal movement on the link.

9. In an electric switch, liquid contact circuit closers operable by rotation about their axes, said circuit closers having opposed terminals and being arranged for rotation about spaced axes, contacts frictionally engaging said terminals, said contacts and said terminals having interfitting projections and depressions providing bearing surfaces whereby the circuit closers are supported for rotation by said contacts, the diameter of said bearing surfaces being relatively

great compared to the wall thickness of said projections and depressions, a reciprocable link having pivotal connections with the terminals of said circuit closers whereby the circuit closers are rotated in unison, and resilient means exerting a force on said link perpendicular to its reciprocal movement whereby the contact pressure between said terminals and said contacts is increased.

10. In an electric switch, four electric contact circuit closers each having opposed terminals, said circuit closers being arranged in pairs with the inner terminals of each pair opposite each other, a pair of contact strips each frictionally engaging the inner terminals of one pair of circuit closers, a pair of contact strips each frictionally engaging two of the outer terminals of the circuit closers on the same side of the switch, said strips and said terminals having interfitting projections and depressions providing bearing surfaces whereby the circuit closers are supported for rotation, the diameter of said bearing surfaces being relatively great compared to the thickness of the strips, and means for rotating said circuit closers in unison, said circuit closers being arranged so that a circuit is completed from one of the contacts connected to the inner terminals of the circuit closers alternatively to one of the contacts connected to the outer terminals.

11. In a double pole reversing switch, four liquid contact circuit closers, each having opposed terminals, one pair of the circuit closers being arranged adjacent each other on one side of the switch and the other pair of the circuit closers being arranged adjacent each other on the other side of the switch, the circuit closers on one side of the switch being opposite the circuit closers on the other side of the switch, a pair of contacts on opposite sides of the switch respectively connecting two of the terminals of the adjacent circuit closers, and a pair of contacts respectively connecting the remaining terminals of the opposite circuit closers.

ROBERT F. SAMBLESON.
